UNITED STATES PATENT OFFICE.

ESTLE NORMAN NOLAN, OF LOUISVILLE, KENTUCKY, ASSIGNOR OF ONE-FOURTH TO
J. W. NOLAN, OF HARLAN, KENTUCKY.

FAN ATTACHMENT FOR AUTOMOBILES.

Application filed January 31, 1927. Serial No. 164,920.

The invention relates to a novel form of fan attachment for automobiles, said attachment being designed primarily for use as part of a combined heating and ventilating means.

One object of the invention is to provide a new and improved fan whose casing is provided with novel means for mounting it upon the conventional automobile motor, provision being made whereby the casing may be properly positioned to effectively engage a driving pulley of the fan with the usual fan belt of the motor.

Yet another aim is to provide an attachment for automobiles, which will be rather simple and inexpensive, yet will be efficient, reliable and in every way desirable.

With the foregoing in view, the invention resides in the novel subject matter herein-
after described and claimed, the description being supplemented by the accompanying drawings.

Fig. 1 is an elevation partly in section, showing the application of the invention to an automobile rather diagrammatically.

Fig. 2 is a top plan view of the parts shown in Fig. 1.

Figs. 3 and 4 are respectively a front elevation and a rear elevation of the fan, each view being partly in section.

Fig. 5 is a top plan view of the fan.

Fig. 6 is a central vertical longitudinal section on line 6—6 of Fig. 5.

The construction selected for illustration in the present application will be rather specifically described, with the understanding however that within the scope of the invention as claimed, variations may be made.

The fan embodies a fan proper F and a casing C. This casing embodies a cylindrical side wall 7 having a laterally projecting discharge neck 8 and provided with upper and lower bosses 9 and 10 in which vertically alined studs 11 are threaded, said studs being provided with nuts 12 by means of which they may be secured to upper and lower brackets or supports 13 and 13'. Integral with the side wall 7, is a front end wall 14 which is provided with an air inlet elbow 15 integrally joined thereto, and is equipped also with a central, shaft bearing 16. The elbow 15 is provided with a suitable air filter or screen 17.

The rear end wall 18 of the casing C is provided with a central, shaft bearing 19

and with a boss 20 in which a threaded stud 21 is anchored, said stud being at an angle to the common axis of the studs 11 and being provided with a nut 22, whereby it may be secured to a third bracket or strap 23. This rear wall 18 is removably secured to the side wall 7, by a plurality of machine screws 24.

The shaft 25 of the fan F is rotatably received in the bearings 16 and 19 and projects forwardly from the elbow 15, the forwardly projecting portion being provided with a flanged driving pulley 26.

The fan is attached to the automobile motor in a manner which will be clear from Figs. 1 and 2. The bracket 13 is anchored by means of one of the cylinder head bolts B, the bracket 13' is anchored by one of the usual crank case bolts B', and the bracket 23 is secured to the motor by one of the bolts B² which connect the water return pipe P with the engine jacket. When the fan is mounted in this manner, its pulley 26 is positioned to engage the usual belt b of the automobile fan f. When installing the device, the two vertically alined studs 11 which pass turnably through openings 27 in the brackets 13 and 13', permit turning of the fan casing about a vertical axis to properly position the pulley 26 for cooperation with the belt b. Then, by securing the third bracket 23, the casing is effectively held against further turning about the aforesaid axis.

An air conducting pipe 28 has been shown extending rearwardly from the air discharge neck 8, the front end of said pipe merely fitting into an opening 29 in the rear side of said neck. This pipe is preferably, although not necessarily formed from thin sheet metal. A branch 30 is shown rising from the pipe 28 to a suitable register 31 which may well be positioned under the front portion of the front automobile seat, and a similar arrangement may be provided in connection with the rear seat. Thus, any current of air which is permitted to flow rearwardly throughout the length of the pipe 28, will discharge through the registers 31 to effectively ventilate the car body. Provision is made however, whereby the air may be shunted from the pipe 28 and heated before it is discharged into the body.

32 designates an air heating jacket surrounding a portion of the exhaust pipe E from the motor. Front and rear caps 33 and 34 are provided for this jacket, and a

branch pipe 35 connects the front cap with the pipe 28, while the rear cap 34 is connected with an appropriate register 36 disposed in the floor-boards or at other desired location. My preference, the jacket 32 is flexible to readily adapt itself to the curvature of the pipe E.

A suitable valve 37 is provided at the junction of the pipe 28 with the branch 35, and 10 by means of an appropriate control 38 running to a point within reach of the driver, this valve may be moved to either of two positions. When the valve is in one position, the cool air from the fan F may pass 15 rearwardly through the piping 28 for discharge through the registers 31 to ventilate the car. However, when the valve is in its other position, the piping 28 is obstructed directly behind the branch 35, forcing the 20 air from the fan to pass through this branch into the air heating jacket 32. In this jacket, the air is effectively heated by contact with the exhaust pipe E, and the heated air discharges into the car body through the register 36.

Excellent results are obtainable from the general construction and arrangement shown and described, such construction and arrangement being therefore preferably followed. However, within the scope of the invention as claimed, variations may be made.

I claim:

1. In an air supply device for a motor vehicle body; a fan having a casing and a belt

35 pulley in front thereof for contact with the conventional fan belt, upper and lower attaching brackets contacting with the upper and lower sides of said casing and having vertically aligned openings, vertically aligned threaded fasteners passing rotatably through 40 said openings and connected with the casing, said fasteners permitting turning of the casing about the common vertical axis of said fasteners when the latter are loosened, and an additional attaching bracket connected with the casing at a point laterally offset from said axis, said brackets being adapted for attachment to the automobile motor, said additional bracket then holding the casing 45 against turning about said axis.

2. In an air supply device for a motor vehicle body; a fan casing comprising a cylindrical side wall having upper and lower vertically aligned threaded studs for connection to attaching brackets and provided also with 50 an integral lateral discharge neck, a front wall integral with said side wall and having an integral air inlet elbow and a central shaft bearing, and a rear wall detachably secured to said side wall and having a central shaft bearing, said rear wall being provided also with a threaded stud whose axis is at an angle to the common axis of said 55 vertically aligned studs.

In testimony whereof I have hereunto af- 60 fixed my signature.

ESTLE NORMAN NOLAN.
